(57) CLAIM

I claim the ornamental design for a three-lobed jumpring, as shown and described.

DESCRIPTION

FIG. 1 is a front and/or a rear view of the claimed three-lobed jumpring having circular curves.

FIG. 2 is a front and/or a rear view of the claimed three-lobed jumpring having less circular curves than shown in FIG. 1.

FIG. 3 is a front and/or a rear view of the claimed three-lobed jumpring having still less circular curves than shown in FIGS. 1 and 2.

FIG. 4 is a front and/or rear view of the claimed three-lobed jumpring having still less circular curves than shown in FIGS. 1, 2 and 3; and,

FIG. 5 is a front and/or rear view of the claimed three-lobed jumpring having still less circular curves than shown in FIGS. 1, 2, 3 and 4.

Formed of, or resembling wire whereby the bottom end is joined to a jewelry element such as a bezel, for example, by solder, and the top end is loosely joined to another jumpring, which may be a standard round jumpring. The three-lobe jumpring of this invention viewed from a top view is substantially linear, any deviation from linearity being where the wire crosses itself.
